CLAIM

The ornamental design for an antenna, as shown and described.

DESCRIPTION

FIG. 1 is a front elevational view of an antenna showing my new design, the rear being a mirror image;

FIG. 2 is a top plan view thereof;

FIG. 3 is a left side elevational view thereof;

FIG. 4 is a right side elevational view thereof; and

FIG. 5 is a bottom plan view thereof.

*Fig. 1.**Fig. 4.**Fig. 2.**Fig. 3.**Fig. 5.*
